UNITED STATES PATENT OFFICE.

WILLEM VAN EE AND WILLIAM J. GEIST, OF LONG BEACH, CALIFORNIA.

TUBING ROLLER.

Application filed May 31, 1927. Serial No. 195,365.

This invention has to do with a tubing roller and has particular reference to a device useful for rolling boiler tubes, or the like, to make them tight in a boiler plate, or 5 drum.

The tool provided by this invention is useful, generally, for rolling boiler tubes, or the like, and is particularly suited for use where the tubes are in one side of a cylindrical 10 drum, or the like, and the tool must be passed through small openings in the opposite side of the drum to reach the tubes. Tubes connected into a cylindrical drum, or the like, as above mentioned, work loose from time to 15 time, making it necessary for them to be re-rolled or tightened. As a result of this condition, some of the tubes are rolled more than others so that the inside diameters of 20 the tubes vary. Under the practice generally followed, it is necessary to use several different sized rolling tools to meet this variation in the tubes. This handling of several 25 different sized rolling tools not only involves the expense incidental to having several tools, but consumes considerable time in obtaining the proper size tool for a given tube and often results in the smaller size tools being forced beyond their limit.

It is an object of this invention to provide 30 a tube rolling device which will operate effectively in tubes of various internal diameters so that a single tool will satisfactorily meet the conditions above referred to.

It is another object of this invention to 35 provide a tube roller which is simple, effective and durable in construction.

The various objects and features of the invention will be best and more fully understood from the following detailed description 40 of a typical form and application of the invention, throughout which description reference is had to the accompanying drawings, in which:

Fig. 1 is a view illustrating the rolling 45 tool provided by this invention in operating position in a tube;

Fig. 2 is a longitudinal, sectional view of 50 the rolling tool showing it in the collapsed position;

Fig. 3 is a transverse, sectional view, taken 55 as indicated by line 3-3 on Fig. 2;

Fig. 4 is a view similar to Fig. 2, showing 60 the tool in the expanded position; and

Fig. 5 is a transverse, sectional view, taken 65 as indicated by line 5-5 of Fig. 4.

The tool provided by this invention in-

cludes, generally, an annular body 10, a plurality of rollers 11, carriers 12 for the rollers, mounting means 13 connecting the roller carriers 12 with the body 10, and an operating mandrel 14.

The body 10 is an annular or ring-shaped member which serves as a mounting or carrier for the roller carriers 12. The outside diameter of the body 10 is such as to allow the body to be freely passed through a hole such as may occur in a boiler plate or drum opposite the tube to be rolled. The inside diameter of the body, that is, the opening in the body, is made to properly pass or accommodate an operating mandrel. As far as this invention is concerned, any suitable operating means or mandrel may be used to operate the tool.

In accordance with the present invention, 75 the tool may be provided with a plurality of rollers and roller carriers. In the drawings, we have, for purpose of example, disclosed a form of the invention including three roller carriers 12. Each carrier 12 is arcuate or segmental in form and has a socket 16 formed in it from its inner end to carry a roller 11. The rollers 11 are, of course, round in cross section and the sockets in the carriers are made to hold the rollers with suitable working clearance. The diameter of the rollers 11 is greater than the thickness of the carriers and the sockets 16 are formed in the carriers so that the rollers project from the inner and outer sides of the 80 carriers, as clearly shown in Fig. 5 of the drawings. In the preferred construction, the sockets are pitched or inclined slightly from a position parallel with the longitudinal axis of the tool, as shown in Figs. 1 and 85 5 of the drawings. Further, the rollers are preferably tapered slightly to correspond to the taper of the operating mandrel so that they engage the tube uniformly throughout 90 their length.

The mounting means 13 provided by this 95 invention connects the carriers 12 with the body 10 so that they are independently movable radially with reference to the body. Each carrier 12 is provided at its inner end with an enlargement or head 20 provided with a recess 21 to receive a lug 22 projecting from the side of the body 10. A mounting pin 23 is carried by the head 20 to extend through the recess 21 and through an opening 24 in the lug 22. In the particular 105 form of the invention shown in the draw- 110

ings, the pin 23 is tightly carried by the head 20 and fits more or less freely through the opening 24 in the lug 22. For the purpose of allowing the desired radial movement of the carrier with reference to the body, the opening 24 in the lug is made in the form of a radially disposed slot which allows the pin to move between the positions shown in Figs. 2 and 4 of the drawings. The heads of the carriers slidably engage the body 10 so that the carriers are braced by the body.

The enlargements or heads 20 at the inner ends of the carriers 12 project radially from the roller carrying portions of the carriers 15 and thus operate as stops to limit the movement of the tool into a boiler tube T, or the like. The manner in which the heads 20 limit the movement of the tool is clearly illustrated in Fig. 1 of the drawings.

20 In the arrangement provided by this invention, the inner ends of the roller carrying sockets 16 terminate at or in the recesses 21 so that the lugs 22 are at the inner ends of the sockets to hold the rollers in the sockets 25 when the tool is assembled as shown throughout the drawings.

In using the tool, it is arranged in operating position in the boiler tube T with the various parts retracted, as shown in Figs. 2 30 and 3 of the drawings. It is to be noted that the tool, when in this position, is comparatively small in diameter, being sufficiently small to freely pass through a hole that will pass the tube T. When the tool is 35 in place in the tube T, it is operated through the medium of the mandrel 14 so that the rollers 11 are expanded radially into pressure engagement with the interior of the tube T. As the mandrel 14 is rotated in the manner common to devices of this character, the rollers 11 operate on or roll the tube T into the opening 30 provided in the boiler drum or plate D. It is to be noted that the construction provided by this invention allows 40 for a substantial amount of radial movement or expansion of the rollers, making the tool useful and effective in tubes of various internal diameters.

Having described only a typical preferred 45 form of our invention, we do not wish to limit ourselves to the specific details set forth, but wish to reserve to ourselves any changes or variations that may appear to those skilled in the art or fall within the scope of the 50 following claims.

Having described our invention, we claim:

1. A tubing roller including an annular

body, a plurality of carriers arranged at one side of the body about the axis of the body, means connecting the body and carriers so that the carriers are individually movable radially, and rollers rotatably mounted in the carriers, said means including lugs on the body projecting into recesses in the carriers and pins connecting the carriers and lugs. 60

2. A tubing roller including an annular body, a plurality of carriers arranged at one side of the body about the axis of the body, means connecting the body and carriers so that the carriers are individually movable radially, and rollers rotatably mounted in the carriers, said means including lugs on the body projecting into recesses in the carriers and pins connecting the carriers and lugs, the lugs having radially disposed slots carrying 70 the pins. 75

3. A tubing roller including an annular body, a plurality of lugs on one side of the body, a plurality of carriers having recesses in their inner ends to receive the lugs, means connecting the carriers and lugs, the carriers having sockets extending into them from the recesses, and rollers carried in the sockets. 80

4. A tubing roller including an annular body, a plurality of lugs on one side of the body, a plurality of carriers having recesses in their inner ends to receive the lugs, pins connecting the carriers and lugs, the carriers having sockets extending into them from the recesses, and rollers carried in the sockets. 85

5. A tubing roller including an annular body, a plurality of lugs on one side of the body, a plurality of carriers having recesses in their inner ends to receive the lugs, means connecting the carriers and lugs so that the carriers are independently movable radially of the body, the carriers having sockets extending into them from the recesses, and rollers carried in the sockets. 90

6. A tubing roller including an annular body, a plurality of lugs on one side of the body, a plurality of carriers having recesses in their inner ends to receive the lugs, pins connecting the carriers and lugs, the lugs having radially disposed slots passing the 100 pins, the carriers having sockets extending into them from the recesses, and rollers carried in the sockets. 105

In witness that we claim the foregoing we have hereunto subscribed our names this 16th day of May, 1927. 110

WILLEM VAN EE.
